SHIPPING PACKAGE FOR PRESS INKING ROLLS

Louis C. Ambrette, Westbury, and John W. McNeil, Brooklyn, N. Y.

Application December 24, 1949, Serial No. 134,986

2 Claims. (Cl. 206—65)

1

This invention relates to novel method and means for packaging printing press inking rolls for transportation.

Inking rolls used in printing presses ordinarily each comprise a steel shaft upon which is fixed a roll body made of a gelatin composition. For efficient service, when such inking rolls are mounted in printing presses, the peripheral surfaces thereof must be of true cylindrical contour, free from dents or other deformation, otherwise the surfaces of the rolls will not make proper inking contact with the type faces over which they are moved for transfer of ink to the type. If the rolls are dented, deformed, or out of true with respect to their peripheral surfaces, they may fail to contact the entire area of type surfaces, and parts of said type surfaces may be skipped without transfer of necessary ink thereto. Since the surface of a gelatin inking roll is very susceptible to injury by anything accidentally brought into contact therewith, even by mere contact of the hands therewith when handling the roll, not only must great care be exercised in the handling of the roll, but, if packed for transportation, the same must be so supported within the shipping container as to be incapable of shifting movement therein, and the support must be such that the roll surface is held spaced away from the container walls and adjacent rolls, whereby the roll surface is guarded against injury by contact with said walls or adjacent rolls. By reason of this shipping containers for gelatin inking rolls, as heretofore provided, have comprised expensive wooden boxes fitted with complicated interior construction by which the roll or rolls are supported therein.

Having the above stated facts in mind, it is an object of this invention to provide a relatively inexpensive paperboard carton as a shipping container for gelatin inking rolls, including novel removable roll supporting members also made of paperboard; said members being of such novel construction and form that, in addition to providing the required segregating support of one or more rolls when inserted therewith within the carton interior, they also provide means for conveniently handling the rolls, when entering or removing the same from the carton interior, all without necessity for touching the sensitive roll surfaces.

The invention has for another object to provide a novel method of assembling and handling gelatin inking rolls during the operations of packaging the same, including the provision of a novel assembling rack for disposing the rolls subject

2

to application thereto of the aforesaid supporting and handling members which form elements of the aforesaid shipping carton.

The accompanying drawings illustrate the novel method and means for packaging printing press inking rolls according to this invention. In said drawings:

Fig. 1 is a longitudinal sectional view of a paperboard shipping carton showing in side elevation a plurality of gelatin inking rolls entered therein as operatively assembled with novel removable supporting and handling members therefor, this view showing by broken lines the assembly of rolls and supporting members as handled for insertion in or removal from the carton; Fig. 2 is a top plan view of the packed carton shown in Fig. 1; and Fig. 3 is a transverse vertical sectional view of said packed carton.

Fig. 4 is a plan view of a blank from which a roll supporting and handling member is made; Fig. 5 is a front face elevational view of a completed supporting and handling member; Fig. 6 is a rear face elevational view of the same; and Fig. 7 is a vertical longitudinal sectional view of the same, taken on line 7—7 in Fig. 5.

Fig. 8 is a side elevational view of an assembling rack for disposing a plurality of inking rolls subject to the application of the supporting and handling members thereto as shown; and Fig. 9 is a transverse vertical sectional view, taken on line 9—9 in Fig. 8, the rolls being indicated by broken lines.

Similar characters of reference are employed in the above described views, to indicate corresponding parts.

Referring to the drawings, the novel supporting and handling members used, according to this invention, in the packaging of one or more gelatin inking rolls or the like, will first be described; said members being generally indicated by the reference character 10.

Each supporting and handling member 10 is formed from a blank of suitable sheet material, such e. g. as laminate corrugated paperboard. The blank comprises a rectangular body 11, from the respective scored margins 12 of which extend a top panel 13, a bottom panel 14 and side panels 15. Extending from the scored end margins 16 of both the top panel 13 and the bottom panel 14 are coupling panels 17. To form the blank into a supporting and handling member 10, the top panel 13 and the bottom panel 14 are each folded back to extend perpendicular to the plane of the body portion 11, and the coupling panels 17 are folded back relative to the thus disposed

top and bottom panels so as to extend inwardly and right angularly thereto. Following this, the side panels 15 are each folded back perpendicular to the plane of the body portion 11, and so as to overlie the back-folded coupling panels 17, being thereupon suitably secured to the latter, as e. g. by means of fastening staples or wire stitching 18. The supporting and handling member 10, as thus produced from the blank, is in the form of a rearwardly open rectangular box-like structure. The dimensions of the blank and its panels are so predetermined that the resultant box-like structure corresponds in height and width to the internal height and width of a shipping carton within which it is to be used. The free marginal portions of the top and bottom panels 13 and 14 are cut away intermediate their ends and to an appropriate depth, whereby to provide finger insertion passages 19 which facilitate handling thereof, as will presently appear. The body portion 11 of the blank, which forms the perpendicular front wall of the supporting and handling member 10, is provided with at least one opening 20, and ordinarily with a plurality of such openings 20 arranged in suitably grouped and relatively spaced disposition. These openings 20 are adapted to receive therethrough the end portions of shafts S of inking rolls R, when supporting and handling members 10 are operatively assembled in carrying and supporting relation to the latter. If the material, of which the members 10 are made, is strong and sufficiently wear resistant, the perforations need not be reinforced. It is preferable, however, especially if the material of the members 10 is one of comparatively soft character or of light weight, to reinforce the margins of said perforations 20. For this purpose, eyelets or grommets 21, of metallic or other rigid material, are mounted in and through the openings 20, and are suitably clinched or otherwise fastened to the body portions 11. Such eyelets or grommets 21 provide strong and durable or wear resisting support for the shafts S of the rolls R.

In the use of the supporting and handling members 10, the same are used in pairs whereby they may be respectively applied to opposite ends of the shaft or shafts S of the roll or rolls R to be supported and carried thereby. To this end, the free end portions of the roll shafts are passed through the openings 20 or the eyelets or grommets 21 of said members 10 so that the roll or rolls are supported in extension between the pair of members 10. When the members 10 and rolls R are thus assembled, the operator may pass the fingers of his hands through the topmost finger insertion passages 19 of the members into engagement with the undersides of the top panels 13, and thereupon lift the assembly for packaging handling thereof. This is shown by both the broken line representation of such assembly which is included in Fig. 1 and in Fig. 8. As thus handled, the assembly can be positioned over the open top of a shipping carton 22 (see Fig. 1), and then lowered by the hands into the interior of the latter, so that the opposite members 10 are respectively deposited in the opposite ends of the carton interior, contiguous to the end walls of the carton (see Figs. 1 and 2), with the rolls R supported by and between the members in such manner as to be securely and immovably held out of possible contact either with the carton walls or with each other. By such handling of the assembly, there is no necessity for touching the sensitive surfaces of the rolls R with the hands, or

of allowing the rolls to come into contact with anything by which the sensitive surfaces thereof might be marred or injured.

Owing to the provision in the members 10 of the indenting finger insertion passages 19, the member engaging fingers of the operator are not obstructed or interfered with by the carton end walls, and therefore the fingers may enter the carton interior with the assembly when the operation of inserting the assembly into the carton is undertaken, and after such insertion the fingers may be easily withdrawn through said passages 19. Likewise, to withdraw the assembly from the carton, when unpacking the same, the fingers can be freely inserted into the carton through said passages 19 and into lifting engagement with the members 10, so that the assembly can be conveniently manually withdrawn from the carton interior, again without necessity for touching the rolls R or subjecting the latter to risk of injury.

It will be noticed that both the top and bottom panels 13 and 14 of the members 10 are shown provided with the finger insertion passages 19. This, of course, is not essential, and no limitation 25 in this respect is intended, since the top panels alone may be so provided which is all that is necessary. It may be desirable, however, to provide said passages 19 in both the top and bottom panels, since by so doing the members 10 are rendered more conveniently reversible.

After an assembly of rolls and supporting members 10 is entered in the carton 22, the latter may be closed and sealed for transportation. It will be obvious that the carton 22 may comprise one 35 of any suitable structure or kind.

As a part of the novel roll handling and packaging method, the invention further comprehends provision of means for assembling the rolls R to be packed preparatory to application thereto of the supporting and handling members 10, and in such manner that necessity for touching the sensitive surfaces of the rolls is avoided. The means for this purpose comprises a roll assembling rack, an illustrative form of which is shown in Figs. 8 and 45 9. This rack comprises a base 25, which is supported by legs 26. The base 25 is provided with an elongated slot 27. Mounted on the base, subject to adjusting movement along the same toward and from one another, are a pair of transverse upright rack standards 28 having foot pieces 50 29 slidably supported on the base. The rack standards are adapted to be fixed to the base in adjusted relatively spaced disposition by clamp bolts 30 which engage through the foot pieces 29 and through the slot 27 of the base. Each rack standard 28 is provided with one or more upwardly open, preferably perpendicular, bearing slots 31. Said bearing slots vary in length and are suitably relatively spaced so that their bottom terminal ends are grouped in correspondence 55 to the desired relative spacing of rolls R, when a plurality of the latter are to be assembled in the group relation which they are to occupy when packed in a shipping carton.

In the use of the assembling rack for practice 60 of the packaging method according to this invention, the rack standards 28 are adjusted to a spaced relation adapted to accommodate extension of rolls R therebetween, with the free end portions of the roll shafts S resting in the bearing slots 31, and so as to project outwardly beyond the outer faces of said rack standards. In thus mounting the rolls R in the assembling rack, the rolls can be handled by their shaft ends so 70 that there is no necessity for touching the sensi-

tive surfaces of the rolls. After the rolls R are mounted in the assembling rack, the supporting and handling members 10 are opposed to the outwardly projecting end portions of the roll shafts S, and then slid onto said shafts, so as to engage the latter through the openings 20 or eyelets or grommets 21 of the supporting and handling members (see Fig. 8). The supporting and handling members being thus operatively assembled with the rolls R, said members can be grasped by the operator's hands and the entire assembly lifted out of and away from the assembling rack (see broken line representation of the lifted assembly shown in Fig. 8). Being thus removed from the assembling rack, the operator, by means of the supporting and handling members 10, can carry the assembly to a carton 22 in which the same is to be packed, and then insert the assembly into said carton in the manner already hereinabove described.

From the above it will be obvious that the packaging method and means according to this invention permits required handling of the rolls without necessity for touching at any time the sensitive surfaces thereof or otherwise subjecting the rolls to risk of injury; and also that the rolls will be immovably supported within a carton in which they are packed for transportation.

It will be understood that the number and group arrangement of a plurality of rolls desired to be packed for transportation may be widely varied, and consequently the arrangement and number of the openings 20 or eyelets or grommets 21 of the supporting and handling members 10 may be such as to accommodate any selected number and grouped arrangement of the rolls.

Although the invention has particular utility with respect to the handling and packed transportation of gelatin inking rolls for printing presses, it will nevertheless be understood that the invention may be practiced and used with other kinds of rolls or devices in the packing of which it is desirable to support the same immovably within the interior of the package and in desired segregate relation.

Having now described our invention, we claim:

1. A shipping package for press inking rolls comprising an elongated container of rectangular cross-section and provided at its open top side with closure means, and a supported roll assembly within said container adapted to be entered therein or removed therefrom as a unit without necessity for directly handling the rolls per se, said assembly comprising a pair of out-

wardly endwise open hollow rectangular supporting members sized to snugly fit transversely within the container respectively at opposite ends of the latter with their outwardly open ends abutting the container end walls, the inner closed end walls of each supporting member having spaced perforations, corresponding perforations of said closed end walls of the respective supporting members being in longitudinally aligned opposition, a plurality of rolls extending between said supporting members, said rolls having endwise projecting shaft portions respective free ends of which are engaged through corresponding aligned perforations in the closed end walls of said supporting members, whereby to support and carry said rolls in longitudinal extension between said supporting members, and uppermost side walls of the respective supporting members having finger insertion passages therein, whereby the opposite supporting members can be simultaneously grasped so as to lower or raise the assembly as a unit to enter the same in or remove the same from the container without necessity for touching the supported rolls.

2. A shipping package for press inking rolls having a supported roll assembly as defined in claim 1, wherein the perforations of the closed end walls of the supporting members are reinforced against rupture and mutilation by metallic grommets.

LOUIS C. AMBRETTE.
JOHN W. McNEIL.
